UNITED STATES PATENT OFFICE.

GEORGE L. STREBLER, OF ST. LOUIS, MISSOURI, ASSIGNOR TO STREBLER APPLIANCES, INC., OF ST. LOUIS, MISSOURI, A CORPORATION OF DELAWARE.

PUMP.

Application filed December 4, 1925. Serial No. 73,106.

My invention relates to power driven pumps and has for its object to provide a pump which is a distinct and practical improvement to overcome certain practical objections to, and defects in, the present types of pumps which have the connecting rod pivotally mounted upon a wrist-pin within the piston and the opposite end connected to a crank-shaft, or its equivalent.

Another object of the invention is to provide a pump structure wherein the axis of the driving members for imparting reciprocating movement to the pistons, are disposed in parallel relation to the axis of the cylinders and pistons at all points of the revolution of the actuating means for said driving members.

A still further object of the invention is to provide wrist-pins for the pistons which extend beyond the peripheral face thereof upon opposite sides thereof and extend through slotted openings in the walls of the cylinders and upon which extended wrist-pins are positioned slidable cross-heads, the longitudinal axis of which are disposed at a right angle to the axis of the wrist-pins and the axis of the cylinders and pistons, and upon which cross-heads are mounted facial slotted driving heads of the driving members for alternate sliding movement upon said cross-head for imparting reciprocating movement to the pistons through the medium of driven eccentrics.

A still further object of the invention is to unite each pair of cross-heads upon either side of opposed cylinders and to mount them for reciprocating movement upon slide-bars so that the pressure exerted by the driving members through the medium of suitable actuating means bear on the slide-bars and is resisted thereby.

A further object of the invention is to provide a pump structure applicable to domestic and light commercial electric refrigerators wherein the peculiar structure thereof serves to provide an oil separator within the pump to prevent an excessive amount of lubricant from entering the cylinders for transmission into the high pressure pipe line with the compressed gases to be condensed, or when used as an air compressor to eliminate oil from contaminating the compressed air.

A still further object of the invention is to provide a pump which possesses advantages in points of simplicity and efficiency

and at the same time proves itself comparatively inexpensive in manufacture.

With the above and other objects in view which will be apparent hereinafter, the invention consists in the novel features of construction, arrangement and combination of parts hereinafter more fully described and finally pointed out in the claims hereto appended.

Referring to the drawings forming a part of this specification wherein like characters of reference denote similar parts throughout the several views:

Fig. 1, is a side elevation of a pump with the case in sectional elevation and embodying the features of my invention.

Fig. 2, is a longitudinal vertical sectional view of the pump.

Fig. 3, is a horizontal sectional view of the pump.

Fig. 4, is a transverse vertical sectional view of the pump midway the ends thereof.

Fig. 5, is a transverse vertical sectional view of the pump through one of the pistons.

Fig. 6, is an assembly view of an automatic electric refrigerating apparatus unit embodying the pump.

While I have shown by reference to Fig. 6, the pump as used in connection with an electric refrigerating system, it is, of course, understood that the pump itself is applicable to other uses, such as an air compressor, water pump, vacuum pump, motor, steam engine and the like.

In carrying out the aim of my present pump construction, I employ a suitable hollow case body 1 of any suitable size and shape. The case body 1 is provided with suitable supporting legs 2, or their equivalent, which can be secured to a suitable base by means of suitable and well known fastening devices used for such purpose. The case body 1 is provided with suitable heads 3 and 4, either, or both of which may be removably fixed to the case body 1. For illustrative purposes only, however, I have shown the head 3 as integral with the case body 1, while the head 4 is shown as removably fixed to the case body 1 by means of suitable fastening devices, such as suitable screws 5. The head 3 of the case body 1 is provided with a suitable low pressure inlet opening 6 and a suitable high pressure outlet opening 7. The opening 6 may be in the casing body 1, if desired. The upper wall of the casing body 1 is provided upon its inner

face with a pair of suitably spaced inverted recesses or chambers 8 and 9 to provide a pair of spaced opposed baffle walls 10 for each recess. Each pair of walls 10 are provided with 5 opposed laterally directed grooves 11, the purpose of which will be apparent hereinafter. The upper face of the casing body 1 is also provided with a suitable electric motor supporting base 12.

10 The pump mechanism employed in accordance with my invention will now be described.

As clearly shown in Figs. 1 to 5, inclusive, of the drawings, the pump mechanism is represented as comprising a suitable cylinder 15 block 13 disposed, preferably in a horizontal position within the case 1 and held in such position in fixed relation to the case 1 in any suitable manner, but shown in the drawings as held in position by means of suitable screw 20 threaded fastening devices 14, which are receivable in suitable bosses 15. This arrangement provides a three point support for the cylinder block.

The cylinder block 13, shown in the drawings, is provided with duplex cylinder bores, or cylinders designated 16 and 17 which are arranged in opposed relation and in axial alignment. The cylinders 16 and 17 have open outer ends, and their inner ends are 30 separated by means of a suitable partition head 18, which is provided with a transverse bearing bore 19 within which is mounted a suitably driven shaft 20. The shaft 20 is supported at opposite sides of the cylinder 35 block 13 by means of suitable bearings 21 and 22, which in turn are supported by the case heads 3 and 4. One end of the driven shaft 20 extends through the case head 4 and a suitable stuffing box 23 for connection with 40 a suitable source of power.

A pair of suitable pistons 24 and 25 are arranged to reciprocate within the cylinders 16 and 17, respectively. The pistons both move in the same direction, in unison, so that 45 while one piston is compressing a charge in its respective cylinder toward the inner end thereof during the inward stroke of the piston, the other cylinder is taking in a charge to be compressed during the inward stroke 50 of its respective piston, as will be apparent hereinafter.

The pistons 24 and 25 are of peculiar construction in that they are closed by means of a head at both ends. The inner ends of the 55 pistons 24 and 25 are provided with suitable automatic intake valves 26 and 27, respectively to permit a charge to enter their respective cylinders through the inner heads of the pistons during the return, or outward 60 stroke of each piston.

The cylinders 16 and 17 are provided with suitable intake ports 28 and 29, respectively. These intake ports 28 and 29 are so positioned at their lower ends as to communicate with 65 slotted port openings 30 and 31 in the walls

of the hollow pistons 24 and 25, respectively, at all times, regardless of the positions of the pistons, as clearly shown in Fig. 2. The intake ports 28 and 29 extend upwardly through upright tubular extensions 32 and 33 which form a part of each cylinder 16 and 17, respectively. The tubular intake port extensions 32 and 33 extend upwardly into the inverted case recesses or chambers 8 and 9, respectively, a suitable distance, and, are each provided with a peripheral flange, or baffle 34 which are receivable in laterally directed grooves 11 of the spaced baffle walls 10. By this arrangement, it is apparent that due to the fact that the case 1 is filled with oil to a predetermined level designated 35, that regardless of the splashing of the oil by working parts of the pump mechanism, such for instance as eccentrics hereinafter described, the oil will be retarded and baffled and by the aid of gravity will be prevented from entering the upper ends of the intake ports 29 and 30 and finding its way into the hollow pistons 24 and 25 and thence into the compression chambers. The walls of the cylinders and pistons are well lubricated from the open ends of the cylinders, as is manifest.

Gas taken in through the intake ports 28 and 29 from the pump chamber passes into the hollow pistons 24 and 25 through the slotted piston port openings 30 and 31, respectively, and then it passes through the automatic intake valve seat openings 36 and 37 of the pistons 24 and 25, respectively into the compression chambers of their respective cylinders during the outward or suction stroke of the pistons. The gas during the compression stroke of the pistons 24 and 25 is forced out of the compression chambers of the cylinders 16 and 17 through the outlet port openings 38 and 39, respectively in the partition head 18 of the cylinder block 13 and passes over the check valves 40 and 41, respectively in the cylinder block port head 42 and into the delivery ports 43 and 44, respectively, which ports communicate at their upper ends with a single outlet port 45 which latter port communicates with the outlet port 7 in the case head 3, as will be apparent from Figs. 2 and 4.

The means for imparting reciprocating movement to the pistons 24 and 25 through rotary movement of driven means, which is, in its preferred embodiment, the shaft 20, resides in providing the driven means upon opposite sides of the cylinder block 13 with a pair of suitable eccentrics designated 46. The eccentrics 46 are each suitably fixed to the shaft 20 and are each further held against displacement by means of the nuts 47 which nuts have screw threaded engagement with the driven shaft 20 and engage the outer faces of the eccentrics 46, as shown in Figs. 3 and 4.

Mounted upon each eccentric 46 is a strap section 48 of a suitable piston driving member. The strap section 48 of each driving member is provided at one end with a driving head 49 and at the opposite end with a driving head 50. The strap section 48 of each piston driving member is preferably connected with the driving heads 49 and 50 by means of suitable connections, such as arms 51 and 52, respectively. The piston driving members are both arranged to the sides of the cylinder block 13, as clearly shown in Figs. 1, 3 and 4, and the axis, or center lines thereof are each at all times maintained in a position parallel to the axis of the cylinders at all points of the revolution of the eccentrics 41 and merely raising and lowering with relation thereto with the movement of the eccentrics.

The driving-heads 49 of the driving members are each provided with a suitable facial groove 53 upon its inner face, which grooves 53 are disposed at a right angle to the axis of the driving members and to the axis of the cylinder 16. Receivable in the facial groove 53 of each piston driving-head 49 is a suitable vertically disposed cross-head 54 upon which the grooved driving heads 49 slide, or reciprocate in a vertically disposed path, or in other words at a right angle to the stroke of the piston 24.

The cross-heads 54 are mounted to reciprocate upon a pair of spaced slide bars 55 which are arranged upon each side of the cylinder block 13 so that the motion of the cross-heads 54 are coincident with, or parallel to the axis, or center line of the cylinder 16. In order to transmit reciprocating motion to the piston 24, I provide the piston 24 near its outer end with a floating wrist-pin 55'. The wrist-pin 55' extends beyond opposite sides of the piston 24 and extends through opposed longitudinally disposed slotted openings 56 in the wall of cylinder 16 and finally seated at its ends in openings 57 disposed centrally of the cross-heads 54. By this arrangement, both cross-heads 54 must move in a path parallel to the faces of the slide bars 55 on which the cross-heads 54 slide back and forth. In this way, the pressure exerted by the driving members through the eccentric bears on the slide bars and is resisted by them.

The opposite piston driving heads 50 of the eccentric driving members are each provided with a suitable facial groove 58 upon its inner face, which grooves 58 are also disposed at a right angle to the axis of the driving members and to the axis of the cylinder 17. Receivable in the facial grooves 58 of each piston driving head 50, is a suitable vertically disposed cross-head 59 upon which the grooved driving heads 58 slide, or reciprocate in a vertically disposed path in unison with the opposite end driving-heads 49 upon the cross-heads 54, or in other words at a right angle to the axis of

the cylinders and to the stroke of the pistons, as is manifest.

The cross-heads 59 are also mounted to reciprocate horizontally upon the same slide bars 55 that the cross-heads 54 slide upon as the slide bars extend from end to end of the cylinder block 13, so that the motion of the cross-heads 59 will also be coincident with, or parallel to the axis of the cylinders 16 and 17. In order to transmit motion through the driving members to piston 25, I provide piston 25 near its outer end with a floating wrist pin 60 which pin extends beyond opposite sides of the piston 25 and through opposed longitudinally disposed slotted openings 61 in the wall of cylinder 17, and which is finally seated at its ends in openings 62 disposed centrally of the cross-heads 59. By this arrangement of parts, both cross-heads 59 must move, as do the cross-heads 54 which are in a path parallel to the faces of the slide bars 55 upon which all the cross heads slide and to the axis of the cylinders 16 and 17. In this way, the pressure exerted by the driving members through both eccentrics bears on the slide bars 55 and is resisted by them.

Tilting movement of the cross-heads 54 and 59 is made impossible by connecting each pair of cross-heads 54 and 59 by means of a pair of connecting bars 63 which also slide upon the slide bars 55.

It will be apparent from the foregoing description, that at all times during rotary motion of the eccentrics 46, circular motion is imparted to the three points of connection of the driving members with the cross heads and eccentric which causes a straight reciprocating motion of the cross-heads at both ends of the cylinder block. The axis of the driving members are at all times parallel with the axis of the cylinders and pistons although they move above and below the axis of the cylinders and pistons during rotary movement of the eccentrics. Consequently, at all points of each revolution of the eccentrics 46, the driving members at their sliding connection with both pairs of cross heads have a tendency to either pull, or push the cross heads excepting at the two dead points due to the fact that the grooved driving heads are either pushing, or pulling at a tangent during their alternating sliding movement upon the cross heads at a right angle to the axis and stroke of the pistons. That is to say the driving members pull the pistons in their compression stroke and push the pistons in the outward, or intake stroke. The tangent pull and push is set up by the circular motion imparted to the drive heads by the eccentrics revolving within the strap sections of the driving members.

It will be recalled that the oil within the pump case provides a splash system of lubrication for the working parts of the pump and that the intake ports to the hollow pistons and the compression chambers of the cylinders are

so guarded and baffled due to the case walls 10, the upright tubes 31 and 32 and the baffle plates 34 thereof being disposed in laterally disposed facial groove in the case walls 10 which set up considerable resistance to any oil that may have a tendency to find its way to the top of the case chamber with the gas being drawn into the compression chambers of the pump. Thus the gases are substantially free 10 from oil contamination when compressed and discharged from the pump. This arrangement eliminates independent oil separators along the pipe line when the pump is used in domestic or light commercial electric refrigerators, and when the pump is used as an air compressor, only the compressed air is free 15 from oil contamination and yet the pump parts are thoroughly lubricated, as is evident.

A refrigerating system for domestic or 20 commercial use employing the herein-described pump will now be described.

The pump when used in connection with a domestic or a commercial refrigerator is mounted upon and fixed to a suitable base 64 25 and is actuated by means of a suitable electric motor 65 positioned upon and fixed to the motor base 12 upon the top of the pump case 1. The pump is driven through the medium of a belt 66 riding over a pulley 67 30 fixed to the armature shaft 68 of the motor and a pulley 69 fixed to the driven shaft 20 of the pump. The pulley 69 is provided with a plurality of radially directed fan blades 70 which direct a current of air over the pump 35 case 1 thereby eliminating undue heating of the pump. The armature shaft 68 of the motor 65 is also provided with a plurality of suitable suction fan blades 71 positioned beyond the pulley 67.

40 A suitable vertically disposed tubular shell or casing 72 acting as an air conduit is positioned upon the base 64 in advance of the pump and electric motor with the belt pulleys disposed therebetween. The air conduit 72 45 is preferably, although not necessarily provided with an open upper end which is covered by means of a wire mesh closure 73 and is provided at its lower end with a plurality of cool air openings 74. The wall of the conduit adjacent the fan 71 is provided with an air outlet opening 75 in which the suction fan 71 is disposed. Positioned within the air conduit 72 are suitable condensing coils 76 which are connected at their upper ends with 50 a high pressure delivery pipe 77 by means of a suitable coupling 78. The pipe 77 leads from the discharge side of the pump so that gases compressed in the pump can be conveyed to the coils 76 to be condensed therein.

55 The condensed gases or liquid flows from the condensing coils 76 into a suitable liquid receiver 79 through a drain pipe 80 connected with the lower ends of the condensing coils. The discharge end of the liquid receiver is 60 connected with an evaporator head, or cas-

ing 81 by means of a supply pipe 82 which communicates with a valve passage 83 which passage is normally closed by means of a needle valve stem 84 which is actuated by means of a suitable float 85 fixed to the outer 70 end of a lever arm 86 which lever arm is pivotally connected, as at 87, to a bracket 88 within the evaporator head 81. The evaporator head 81 is provided with a plurality of suitable freezing pipes 89 which communicate 75 with the interior evaporating chamber 90 thereof which are filled with a liquid refrigerating agent 91, such as methol chloride, sulphur dioxide, or their equivalent, the level 80 of which is retained at a predetermined level in the evaporator head 81.

Extending into the evaporator above the liquid level therein is a low pressure pipe 92 which is directed from the evaporator head 81 and connected at its opposite end with the pump case 1 so as to communicate with the interior thereof which interior acts as a supply receiver for the gas discharged from the evaporator and from which they are drawn into the compression chambers of the pump 90 cylinders to be compressed and delivered to the condensing coils for condensation thereof for return to the liquid receiver and evaporator as needed, which is determined by the action of the float 85.

95 The starting and stopping of the electric motor 65 is shown as controlled by means of what is commercially known as a mercoid 100 designated 93 which is electrically connected with motor electrical conductors 94 and 95 by means of the conductors 96 and 97, respectively, which are in turn connected with suitable electrical supply conductors 98 and 99, respectively controlled by means of a suitable switch 101. The low pressure pipe 92 is also connected with the mercoid 93 by means of a by-pass pipe 100 so that whenever the pressure within the evaporator reaches a predetermined high degree Fahrenheit, the mercoid is tripped and the electric circuit 105 is closed automatically starting the electric motor for driving the pump. Just as soon as the temperature within the refrigerator has again reached its predetermined low degree 110 Fahrenheit, the mercoid is again tripped and the electric circuit to the motor 65 is opened.

115 What I claim is:

1. In a pump of the class described, piston driving mechanism including a pair of arms having facially slotted heads at each end thereof and disposed at right angles to the center line of the piston driving mechanism, and means to move the driving mechanism in fixed circular orbital paths in sliding 120 relation with the pistons.

125 2. In a pump of the class described, piston driving mechanism including arms having facially slotted heads at their outer ends and disposed at right angles to the stroke 130 of the pistons and in sliding connection there-

- with to maintain the longitudinal center line of the driving mechanism in parallel relation with the axis of the pistons during the full stroke of the pistons in either direction.
5. 3. A pump of the class described including aligned cylinders and pistons reciprocable therein, supporting means for the cylinders, driven means, side driving members having connection with driven means and with the pistons for imparting reciprocating movement to the pistons, said driving members being so disposed that the longitudinal center line thereof retains parallel relation with the axis of the cylinders during the full stroke of the pistons in either direction.
4. In a pump construction including aligned cylinders, pistons within the cylinders, a pair of eccentrics, means for rotating the eccentrics, elongated means connecting each eccentric with the pistons for reciprocating the pistons and retaining the longitudinal center lines of said means in parallel relation to the axis of the cylinders at all points of a revolution of the eccentrics.
25. 5. In a pump construction including aligned cylinders and pistons, wrist pins carried near the outer ends of the pistons, eccentrically driven side members embracing the cylinders and means for connecting the wrist pins with the eccentrically driven members for holding the longitudinal center line of the driven members in parallel relation with the axis of the cylinders at all points of the stroke of the pistons in either direction.
35. 6. In a pump structure including aligned cylinders and pistons therein, a pair of eccentrics, means for rotating the eccentrics, means movable with the pistons and disposed at right angles to the pistons on opposite sides of the cylinders, driven means mounted upon the eccentrics midway their length having sliding connection with the means movable with the pistons for imparting reciprocating movement to the pistons and to maintain the longitudinal center line of the driven means parallel with the center line of the pistons at all points of a revolution of the eccentrics.
45. 7. In a pump of the class described including aligned cylinders and pistons therefor, wrist pins for said pistons passing through slotted openings in the side walls of the cylinders, piston driving mechanism comprising slide members carried by the wrist pins, means for slidably mounting the slide members upon the cylinders to prevent rotary displacement thereof, eccentrics, means for rotating the eccentrics and connections between the eccentrics and the slide members for reciprocating the pistons, the longitudinal center line of said connections being maintained in parallel relation with the axis of the cylinders at all points of a revolution of eccentrics but permitted to rise and fall with relation thereto during reciprocating movement of the pistons.
8. In a pump of the class described including aligned cylinders, pistons reciprocable therein, tracks extending laterally from the cylinders, slide members mounted upon the tracks and having connection with the pistons and means for connecting the eccentrics with the slide members for imparting reciprocating movement to the pistons in the same direction upon rotary movement of the eccentrics.
9. In a pump structure, aligned cylinders having outlet openings, a hollow piston for each cylinder having a head at each end, said pistons being provided with slotted intake openings in their upper walls registering with slotted openings in the upper walls of the cylinders, valves in the inner heads of the pistons and means movable in circular paths upon opposite sides of the cylinders having connection with the pistons for imparting reciprocating movement thereto.
10. In a pump, the combination of a cylinder, a piston therein, a wrist pin for said piston, means for controlling the admission of a charge to the cylinder through the walls of the cylinder and piston, driving eccentrics on opposite sides of the cylinder and connections between the eccentrics and the wrist pins, the ends of said connections having sliding movement at a right angle to the stroke of the piston.
11. In a pump construction including a cylinder and a piston therefor, mechanism for reciprocating the piston consisting of a driven eccentric, a floating wrist pin carried by the piston and extending at opposite ends through and beyond the side walls thereof, cross heads positioned upon the ends of the wrist pin, means to prevent rotation of the cross heads and connections between each eccentric and each cross head, the axis of said connections being maintained in parallel relation to the axis of the cylinders at all points of a revolution of the eccentrics.
12. In a pump structure, cylinders, pistons workable in said cylinders, wrist pins for said pistons, intake ports leading through the cylinders and pistons to the compression chambers of the cylinders, outlet ports for the cylinders, a pair of side eccentrics, driving means, cross heads carried by the wrist pins and means for transforming rotary motion of the eccentrics into reciprocating motion at the pistons by intervention of the driving means and cross heads into rectilinear motion at all points of a revolution of the eccentrics.
13. In a pump structure, a cylinder block having aligned cylinders, a rotatably mounted driven shaft passing transversely through the cylinder block adjacent the inner ends of the cylinders, pistons working within said cylinders, driving means actuated by said

driven shaft, wrist pins carried by the pistons, the ends of which extend through slotted openings in the side walls of the cylinders, cross heads having connection with the ends of said wrist pins and slidably mounted upon the side walls of the cylinders, and the ends of said driving means having slidably mounted connection with the cross heads for alternate sliding movement thereon at a right angle to the movement of said cross heads for imparting reciprocating movement to the pistons.

14. In a pump structure, a cylinder block having aligned cylinders, a rotatably mounted driven shaft passing transversely through the cylinder block adjacent the inner ends of the cylinders, pistons working within said cylinders, driving means actuated by said driven shaft, wrist pins carried by the pistons, the ends of which extend through slotted openings in the walls of the cylinders, cross heads carried by the ends of said wrist pins and said driving means having slidably mounted connection with the cross heads for alternate sliding movement thereon at a right angle to the movement of said cross heads for imparting reciprocating movement to the pistons, a casing for wholly enclosing the aforesaid instrumentalities, an intake port and outlet port for said casing, said intake opening communicating with the chamber of the casing, the interior of the pistons and with the cylinder and the outlet port communicating with the cylinders only.

15. In a pump structure including aligned cylinders, pistons therein, inlet port and outlet ports, of a rotatably supported driven shaft, eccentrics fixed to said shaft on opposite sides of the cylinders, driving members mounted upon said eccentrics, wrist pins passing through the pistons near the outer ends thereof and passing through opposed slotted openings in the cylinders, cross-heads carried by the ends of said wrist pins on opposite sides of the cylinders, guide bars integral with the cylinders for mounting said wrist pins, facially grooved driving heads at the ends of the driving members mounted upon said cross-heads for vertical reciprocating movement thereon to impart horizontal reciprocating movement to the pistons through the rotary movement of the eccentric embracing the driving members midway their ends.

16. In a pump of the class described, a cylinder block, pistons within the cylinders, wrist pins for said pistons and extending beyond the walls of the cylinders, cross heads positioned upon the ends of the wrist pins, driven means, eccentrics fixed to said driven means, driving means mounted upon the eccentric within which they rotate midway the ends of the driving means and said driving means having facial grooves disposed at a

right angle to the axis of the cylinders and slidably mounted upon said cross-heads for imparting reciprocating movement to the pistons during rotary movement of the eccentric and to maintain the longitudinal center line of the driving members in parallel relation to the axis of the cylinders during the full stroke of the pistons in either direction.

17. In a pump structure, a cylinder block provided with aligned cylinders, a piston operable within each cylinder, piston driving means, eccentric means for imparting movement to said driving means with the longitudinal center line thereof in parallel relation to the axis of the cylinders at all points of the revolution of the eccentric and said pistons including relatively moving members affording connections between the driving means and the pistons and causing the center lines of the driving means to maintain parallel relation with the axis of the cylinders at all points of the revolution of the eccentrics.

18. In a refrigerator pump structure, a hollow casing having an inlet port and an outlet port, aligned cylinders disposed within and fixed to the casing having communication with the outlet port and with the inlet port, the latter through the chamber of the casing, slotted means for permitting a charge to the compression chambers of the cylinders through the pistons during the intake stroke of the pistons, a rotatably supported driven shaft, a pair of eccentrics fixed to said shaft on opposite sides of the cylinders, driving members, heads arranged at the ends of the driving members having facial slots, said driving members being mounted upon said eccentrics midway their ends for imparting reciprocating motion to the driving members, a wrist pin carried near the outer end of each piston, the ends of said wrist pins extending beyond the walls of the pistons and passing through slotted openings in the side walls of the cylinders and members mounted upon the ends of the wrist pins with their longitudinal axis disposed at a right angle to the axis of the wrist pins and mounted for horizontal reciprocating movement upon the side walls of the cylinders to maintain the center line of the driving members in parallel relation with the center line of the cylinders during every degree of the revolution of the eccentrics.

19. In a pump structure, a cylinder including a compression chamber having an outlet and a housing within which the cylinder is fixed, a hollow piston in said cylinder reciprocable relative thereto, an automatic valve mounted in the inner head of the piston, an intake passage in the cylinder communicating at its intake end with the interior of the housing and at its discharge end with a slotted opening in the wall of the piston and a baffle structure adjacent the intake end of the

intake passage for intercepting atomized lubricating oil within the housing whereby said substance is segregated from other fluid gases or air and returned to its base in the housing from which it emanated.

20. In a pump structure, a housing having intake and outlet ports, aligned cylinders cast en bloc having discharge ports at their inner ends, vertically disposed intake passages in their upper walls and having their side walls provided with opposed longitudinally slotted openings, hollow pistons reciprocable within the cylinders having slotted intake ports in their upper walls, valves disposed in the inner heads thereof, lateral extensions upon the pistons working in the slotted opening of the cylinders, slide bars upon the outer side faces of the cylinders, cross-heads positioned upon the lateral extensions and mounted upon said slide bars, said cross-heads being united upon opposite sides of the cylinders, driven eccentrics, pistons connecting and driving means mounted midway their ends upon the eccentrics and having their outer ends slidably mounted upon the cross-heads in such a manner that the axis of the piston connecting means is disposed in parallel relation to the axis of the cylinders at all points of a revolution of the eccentrics.

21. A device of the class described comprising a housing having an inlet, a pair of aligned cylinders en bloc removably fixed within the housing and each having an inlet and an outlet passage, a valve for each cylinder outlet passage, a piston having an inlet and an outlet passage within each cylinder, an automatic valve for each piston outlet passage, baffle means within the housing adjacent each cylinder inlet passage and means for reciprocating said pistons in unison to compress toward the inner ends thereof.

22. A device of the class described comprising a casing made of two sections having an inlet and an outlet passage and a compressor having horizontally disposed aligned cylin-

ders rigidly but removably carried by one of the casing sections through a three point connection therewith.

23. A device of the class described comprising a casing made of two sections having an inlet and an outlet passage, a pair of recesses formed in the upper wall of one section of the case, a compressor having aligned pistons rigidly but removably mounted wholly within the casing, said compressor having inlet passages communicating with the interior of said casing and having outlet passages communicating with the outlet passage of the casing.

24. In a compressor, a housing having a fluidtight chamber formed to receive a lubricant and also a fluid above the surface of the lubricant, pumping mechanism arranged in the chamber and having an inlet projecting thereabove and in free communication with the part of the chamber above the level of the lubricant, and means for operating the pumping mechanism having a part thereof submerged in the lubricant.

25. In a compressor, a housing having a fluidtight chamber formed to receive a lubricant and also a fluid above the surface of the lubricant, a multiple cylinder pump in the chamber having a plurality of separate inlets projecting thereabove and in free communication with the part of the chamber above the level of the lubricant, and a common means for actuating the pumping elements having a part thereof submerged in the oil.

26. In a compressor, a housing having a fluidtight chamber formed to receive a body of the lubricant and also a fluid above the surface of the lubricant, said housing having a pocket disposed above the surface of the lubricant, a pump in the chamber having an inlet pipe which latter extends above the top of the pump and into the pocket, and means to actuate the pump having a part thereof submerged in the lubricant.

In testimony whereof I have hereunto affixed my signature.

GEORGE L. STREBLER.
